US00D599399S

(12) **United States Design Patent**
Hattori

(10) **Patent No.:** **US D599,399 S**
(45) **Date of Patent:** **** Sep. 1, 2009**

(54) **INK CARTRIDGE**

(75) Inventor: **Shingo Hattori**, Nagoya (JP)

(73) Assignee: **Brother Kogyo Kabushiki Kaisha**,
Nagoya-shi, Aichi-ken (JP)

(**) Term: **14 Years**

(21) Appl. No.: **29/318,795**

(22) Filed: **May 28, 2008**

(30) **Foreign Application Priority Data**

Nov. 30, 2007 (JP) 2007-033058

(51) **LOC (9) Cl.** **18-02**

(52) **U.S. Cl.** **D18/56**

(58) **Field of Classification Search** D18/12,
D18/43, 56; 347/85-87

See application file for complete search history.

(57) **CLAIM**

The ornamental design for an ink cartridge, as shown and described.

DESCRIPTION

FIG. 1 is a front, side perspective view of an ink cartridge showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an additional left-side view thereof, shown in an expanded position.

The broken lines are environmental only and form no part of the claimed design.

1 Claim, 5 Drawing Sheets
